Primary Examiner — Natasha Vujcic

(57) **CLAIM**

The ornamental design for an LED Lamp, as shown and described.

DESCRIPTION

1.-3. LED lamp
1.1 is a top perspective view
1.2 is a right side view.
1.3 is a left side view.
1.4 is a front view.
1.5 is a rear view.
1.6 is a top view.
1.7 is a bottom view.
2.1 is a top perspective view
2.2 is a right side view.
2.3 is a left side view.
2.4 is a front view.
2.5 is a rear view.
2.6 is a top view.
2.7 is a bottom view.
3.1 is a top perspective view
3.2 is a right side view.
3.3 is a left side view.
3.4 is a front view.
3.5 is a rear view.
3.6 is a top view.
3.7 is a bottom view.

The broken lines in the drawings illustrate portions of the LED Lamp which forms no part of the claimed design.

(Continued)

The LED lamps create ideal round-the-clock lighting in enclosures and cabinets.
